[57] CLAIM

The ornamental design for burglar alarm housing, as
shown and described.

DESCRIPTION

FIG. 1 is a perspective view of a burglar alarm housing
showing my new design;

FIG. 2 is a side elevational view thereof on a reduced
scale, the opposite side being a mirror-image of FIG. 2;
FIG. 3 is a front elevational view thereof on a reduced
scale;

FIG. 4 is a back elevational view thereof on a reduced
scale; and

FIG. 5 is a top plan view thereof on a reduced scale, the
bottom plan view being a mirror-image of FIG. 5.

FIG. 1
